The ornamental design for an electronics box for engines, as shown and described.

DESCRIPTION

FIG. 1 is a front elevation view of an electronics box for engines showing my new design;

FIG. 2 is a rear elevation view of the electronics box for engines of FIG. 1;

FIG. 3 is a left side elevation view of the electronics box for engines of FIG. 1;

FIG. 4 is a right side elevation view of the electronics box for engines of FIG. 1;

FIG. 5 is a top plan view of the electronics box for engines of FIG. 1;

FIG. 6 is a bottom plan view of the electronics box for engines of FIG. 1;

FIG. 7 is a front, left perspective view from above of the electronics box for engines of FIG. 1; and,

FIG. 8 is a rear, left perspective view from above of the electronics box for engines of FIG. 1.
